BLANK-HOLDER PRESS

Johan A. Muller, Dayton, Ohio, assignor to The
Hydraulic Development Corporation, Inc., Wil-
mington, Del., a corporation of Delaware

Application April 1, 1942, Serial No. 437,303

11 Claims. (Cl. 113—45)

This invention relates to presses and, in particular, to hydraulic presses having blankholding arrangements in association with drawing devices.

In certain presses of this type in which the clamping force is created by relative movement of the press ram and blankholder platen, the clamping cylinder piston arrangement is provided with means for partially balancing forces created in the balancing cylinders so that a materially smaller force is to be derived from the press ram to create the desired clamping action.

Such presses, as heretofore known and disclosed, for instance in Figure 3 of the U. S. Patent No. 2,167,941 to Ernst, require for each clamping cylinder piston arrangement a first cylinder in the press platen, a second cylinder in the press head, and two plungers respectively reciprocable in the said two cylinders and connected with the press platen and the blankholder platen.

It is an object of this invention to provide an improved blankholder press which will be materially simpler in construction and cheaper in manufacture than the presses referred to in the preceding paragraph, without, however, sacrificing the advantages of the latter.

It is another object of the invention to provide a blankholder press having means associated with a blankholder cylinder piston arrangement for partially balancing forces created therein, in which only one clamping cylinder for each clamping cylinder piston arrangement is required.

It is a further object to provide a blankholder press, in which each blankholder cylinder piston arrangement comprises a plurality of hollow clamping pistons.

It is a still further object to provide a blankholder press, in which each blankholder cylinder piston arrangement comprises two plungers extending into one and the same clamping cylinder, which latter is movable relative to said plungers.

It is another object of the invention to provide a blankholder press as set forth in the preceding paragraph, in which the plungers are fabricated of seamless steel tubing.

Still another object of the invention consists in the provision of a blankholder press having each clamping cylinder piston arrangement provided with two clamping pistons, in which the total height of the press is materially reduced over that of similar presses heretofore known.

These and other objects and advantages of the invention will appear more clearly from the fol-

lowing specification in connection with the accompanying drawings, in which:

Figure 1 diagrammatically illustrates a blankholder press according to the invention.

Figure 2 shows a single clamping cylinder piston arrangement in idle position.

Figure 3 is a view similar to Figure 2, but showing said clamping cylinder piston arrangement just prior to the actual clamping action.

Figure 4 shows the arrangement of Figures 2 and 3 in clamping action.

Figure 5 illustrates the first stage of the retraction stroke of the clamping cylinder piston arrangement.

Figure 6 shows the second stage of the retraction stroke of the arrangement of Figures 2 to 5.

Figure 7 diagrammatically illustrates the distribution of forces during the actual clamping action.

20 *General arrangement*

The blankholder press of the present invention is characterized primarily by an improved and simplified clamping arrangement, according to which only one cylinder is provided for each clamping cylinder piston arrangement.

The arrangement is such that two plungers, one of which is stationary, while the other is connected to the blankholder platen, extend into one and the same clamping cylinder, which latter is movable relative to both plungers and actuated by the press ram.

25 *Structural arrangement*

30 Referring now to the drawings in detail and to Figure 1 thereof in particular, the press structure shown therein comprises a press head 10 having a press cylinder 11 in which is reciprocably mounted a press ram 12.

35 The press ram 12 has connected thereto a press platen 13 which, in its turn, carries a punch 14 adapted to pass through a bore 15 in a blankholder platen 16 in order to shape a work piece which is held by the blankholder platen 16 during the drawing or shaping action. The blankholder 16 has connected thereto a plurality of

40 holding members 17 which extend through bores 18 in the press platen 13 and have their upper ends provided with a thread 19 adapted to receive a nut 20. As will be seen from the drawings, the adjustment of the nut 20 varies the maximum distance between the bottom portion of the press platen 13 and the adjacent face of the blankholder platen 16.

45 45 Adjustably mounted in each of the supporting

50 55

members 17 is a threaded rod 21 adapted to engage the head 10 for stripping the work piece from the punch 14. The blankholder platen 16 carries a plurality of hollow plungers 22 which extend into the clamping cylinders 23 supported by and connected to the press platen 13 in any desired manner. The clamping cylinders 23 extend into correspondingly shaped recesses 24 provided in the press head 10.

Connected to the press head 10, for instance by fitting members 25 and screws 26, are hollow plungers 27 extending into the respective cylinders 23, and also adapted to telescope into the hollow plungers 22. It should be noted that the outer diameter of the plungers 27 and the inner diameter of the plungers 22 are so dimensioned that when these plungers are telescoped in each other, there is a marginal area between the outer surface of the plunger 27 and the adjacent inner wall surface of the plunger 22, which will allow fluid to escape from the plunger 22 into the cylinder 23.

The hollow plungers 22 and 27 may, if desired, be manufactured of seamless tubing, which materially facilitates the production of the press and reduces the cost of production, inasmuch as no particular machining operation is required.

The interior of the plungers 27 communicates through bores 28 in the fitting members 25 with a conduit 29 comprising check valves 30 and having branch conduits 31 with check valves 32. The conduit 29 communicates through a conduit 33 with a control valve, generally designated 34. The control valve 34 has an opening 35 continuously establishing communication between a cylinder bore 36 and a fluid tank or reservoir 37 mounted on top of the press head 10. Reciprocably mounted in the cylinder bore 36 is a valve member 37 with two spaced pistons 39, 40, for selectively establishing or preventing communication between the opening 35 and the opening 41, which latter communicates with the conduit 33.

The piston 39 is adapted to be acted upon by pressure fluid conveyed through a conduit 42, whereas the piston 40 is adapted to be actuated by pressure fluid conveyed through the conduit 43. The conduit 42 communicates with a conduit 44 having one end connected to the upper portion of the press cylinder 11, while the other end leads to a four-way valve 45 of any standard design, which may be operated manually by actuation of the lever 46.

The four-way valve 45 has furthermore connected thereto a conduit 47 leading to the fluid tank 37 and a conduit 48 communicating with the conduit 43 and leading to a passageway 49 which, in its turn, is connected to the lower portion of the press cylinder. The valve 45 has connected thereto a further conduit 50 which communicates with the pressure side of a constant delivery pump 51 of any desired type. The suction side of the pump 51 communicates through a conduit 52 with the tank 37.

Branching off from the conduit 29 and respectively associated with the clamping cylinders 23 are conduits 53 with pressure relief valves 54, which are preferably individually adjustable so as to enable different clamping pressures in each of the clamping cylinders.

Operation

It may be assumed that all parts of the press occupy the position shown in Figure 1, and that it is now desired to carry out a working cycle of

the press. To this end, the operator starts the pump 51 and actuates the valve 46 by operation of the lever 46, so that fluid connection is established between the conduits 44 and 50, while the conduits 47 and 48 are brought into fluid connection with each other. Pressure fluid from the pump 51 is then conveyed through valve 45 and conduit 44 into the upper portion of the press cylinder 11. A part of the pressure fluid in conduit 44 passes through conduit 42 and acts upon the piston 39 so as to shift the valve member 38 toward its right hand or closing position, in which fluid connection is interrupted between the conduit 33 and the opening 35. Furthermore, fluid is withdrawn from the lower portion of the press cylinder 11 through the passageway 49, conduit 48 and valve 45, and is exhausted into the tank 37. The press ram 12 then moves downwardly as fast as fluid is expelled from the lower portion of the press cylinder 11.

While the ram 12 moves downwardly, the press platen 13 and the clamping platen 16, suspended thereon by means of the members 17 and nuts 20, move downwardly in unison. During this downward movement, the space between the lower ends of the plungers 22 and the lower ends of the respective plungers 27 increases, thereby creating a suction effect, which causes the check valves 32 to open so that fluid from the tank 37 passes through the check valves 32 and conduits 29 into the respective plungers 27.

As soon as the blankholder platen 16 engages the work piece, it comes to a halt, at which time the clamping cylinder piston arrangement occupies the position shown in Figure 3. The press platen 13, however, continues its downward movement. Due to the downward movement of the press platen 13 and the cylinders 23 connected thereto, relative to the pistons 22, the latter telescope into the cylinders 23, as shown in Figure 4, and cause the creation of clamping pressure. When this pressure exceeds a predetermined value, for which the pressure relief valves 54 have been set, the excessive pressure is relieved through the said relief valves into the tank 37. The press ram 12 and, therefore, also the press platen 13 continue their downward movement so as to cause the punch 14 to shape the work piece to be drawn.

It should be noted that, although the clamping plungers 22 have a relatively large area for effecting the desired clamping of the work piece, only a relatively small clamping force has to be derived from the press ram 12, since a portion of the forces acting in the clamping cylinders is balanced.

The actual distribution of the forces acting in the clamping cylinders will be best understood from a reference to Figure 7 which, in a simplified form, illustrates a clamping cylinder 23 with the clamping plungers 22 and 27 pertaining thereto.

Assuming that the cylinder 23 is moving downwardly, it will be clear that pressure is created in the cylinder 23, since the space filled by the plunger 22 telescoping into the cylinder 23 is larger than the space freed by the lower portion of the plunger 27. Consequently, the forces in the cylinder 23 are composed of the forces acting upon the bottom *a* and rim *b* of the plunger 27, the forces acting upon the bottom *c* and rim *d* of the plunger 22 and the forces acting upon the bottom *e* and top *f* of the cylinder 23.

The forces acting upon the bottom *a* and the rim *b* of the plunger 27 are counterbalanced by

the forces acting upon the central portion of the bottom *c*, which portion has a section equalling

$$\frac{d_1^2\pi}{4}$$

The forces acting on the bottom and top portions of the cylinder 23, the area of which equals

$$\frac{d_2^2\pi}{4} - \frac{d_1^2\pi}{4}$$

balance each other, as will be obvious from the drawing. Consequently, only the forces acting on the bottom portion of the plunger 22, which portion equals

$$\frac{d_2^2\pi}{4} - \frac{d_1^2\pi}{4}$$

is unbalanced, and this force is the only force to be derived from the ram or to be detracted from the force acting upon the ram for maintaining a predetermined clamping pressure on the blankholder platen 16. Therefore, a relatively high clamping pressure is created by the press according to the invention, while only a small portions of this clamping pressure is derived from the press ram.

When the drawing or shaping action has been completed by the punch 14, the operator reverses the position of the valve 45, thereby establishing fluid connection between the conduits 50 and 48, while simultaneously connecting the conduits 47 and 44 with each other.

Pressure fluid is then delivered by the pump 51 through conduit 50 and valve 45 into the conduit 48. From here a part of the pressure fluid is conveyed through conduit 43 to the piston 40, so as to shift the valve member 38 into the position shown in Figure 1, in which fluid connection is established between the conduit 33 and the opening 35. Pressure fluid in the conduit 48 flows through the passageway 49 into the lower portion of the press cylinder 11 and starts the upward or retraction movement of the ram 12.

When the ram 12 and, therefore, the press platen 13 connected thereto, move upwardly, the fluid expelled from the upper portion of the press cylinder 11 escapes through the conduits 44 and 47 into the tank 37. Due to the upward movement of the press platen 13, a relative withdrawal of the clamping plunger 22 from the clamping cylinder 23 is effected and, since the effective area of the plunger 22 is larger than the effective area of the plunger 21, a suction effect is created in the cylinder 23, which causes fluid to flow from the tank 37 through the check valves 32 and plungers 21 into the cylinders 23. Consequently, the blankholder platen 16 remains in its lower position, while the distance between the press platen 13 and the blankholder platen 16 increases. This action is shown in Figure 5.

If, during the upward movement of the press platen 13, the work piece should stick to the punch 14, the blankholder platen 16 will move upwardly together with the press platen 13, so that there will be a space between the upper face of the press platen and the bottom face of the nuts 20. When the knockout rods 21 then engage the press head 10, they will prevent further upward movement of the blankholder platen 16, while the press platen 13 continues its upward movement and, in this way, will strip the work piece off the punch 14 so that the work piece may be removed.

At the end of the first stage of the retraction stroke of the press platen 13, the latter abuts

the nuts 20 and further upward movement of the press platen 13 causes the latter and the blankholder platen 16 to move upwardly in unison. This initiates the second stage of the retraction stroke, as indicated in Figure 6, in which a relative approaching movement is effected between the plungers 22 and 21. This causes fluid to be expelled from the cylinders 23, and to flow through the conduits 28 and 33 and the bores 41 and 35 into the tank 37.

When the press ram 12 has reached the end of its retraction stroke, the operator may stop the pump 51, remove the work piece, and then start a new cycle.

As will be clear from the drawings, the structure according to the invention constitutes a material simplification over the structure of similar presses heretofore known, in particular, only one clamping cylinder for cooperation with two pressing plungers is needed, and no clamping cylinder is required in the press head. This not only saves material and work, thereby speeding up the production of such presses, but also materially decreases the total height and weight of the press.

Although, as mentioned above, it is preferable to make both plungers 22 and 21 hollow so that seamless steel tubing may be used for these plungers, it is, of course, understood that the plunger 21 may, in many instances, be shorter than is shown in the drawings, so that it need not telescope into the plunger 22, in which instance the plunger 22 may be solid without affecting the operation of the press.

It is furthermore to be noted that the arrangement shown in the drawings allows, in a very simple manner, to increase the stroke of the press. All that is necessary in such an instance is merely to exchange the plungers 21 for longer plungers. This is another material advantage over similar presses heretofore known which, for such a purpose, required not only elongated plungers, but also new cylinders.

It will be understood that I desire to comprehend within my invention such modifications as come within the scope of the claims and the invention.

Having thus fully described my invention, what I claim as new and desire to secure by Letters Patent, is:

1. In combination in a press, a press ram for exerting pressure on a work piece, blankholder means for holding said work piece while it is being shaped, and a plurality of clamping cylinder-piston-assemblies operatively connected with said ram and said blankholder means for exerting pressure on the latter in response to a relative movement of said ram and said blankholder means, each of said clamping cylinder-piston-assemblies comprising a clamping cylinder movable by said ram, and also comprising two hollow plungers extending into said cylinder and adapted to be telescoped into each other, one of said plungers being stationary and forming a fluid passage means communicating with the interior of said cylinder, while the other and larger plunger is connected to said blankholder means.

2. In combination in a press, a reciprocable press ram for exerting pressure on a work piece to shape the same, blankholder means for holding said work piece while it is being shaped, a plurality of clamping cylinders arranged to move in unison with said ram, a plurality of first plungers stationarily arranged and respectively extending into one end of said clamping cyl-

inders, and a plurality of second plungers connected to said blankholder means so as to move in unison therewith and respectively extending into the other end of said cylinders, said second plungers having a diameter larger than said first plungers and being adapted in response to relative movement of said ram towards said blankholder means to create clamping pressure in said clamping cylinders and to convey said clamping pressure to said blankholder means.

3. In combination in a press, a press head, a press ram reciprocable in said head for exerting shaping pressure on a work piece, blankholder means for holding said work piece while it is being shaped, said press ram being movable relative to said blankholder means, a plurality of clamping cylinders connected to and movable in unison with said ram and adapted to extend into a recess in said head, a plurality of stationary plungers supported by said head and respectively extending into said cylinder, and a plurality of additional clamping plungers having a diameter larger than said stationary plungers and being connected to said blankholder means, said additional plungers being adapted in cooperation with said cylinders and in response to relative movement of said press ram and said blankholder means to create clamping pressure in said clamping cylinders and to convey said pressure to said blankholder means.

4. In combination in a press, a reciprocable press platen, blankholder means connected with but movable relative to said platen for holding a work piece while it is being shaped, a plurality of clamping cylinders supported by and movable with said platen, a plurality of stationary plungers respectively extending into said cylinders and forming conduit means communicating with the interior of said cylinder, a plurality of additional plungers operatively connected to and movable in unison with said blankholder means and respectively extending into said cylinders, said additional plungers having a larger diameter than said stationary plungers and being adapted in response to a relative movement of said platen towards said blankholder means to create clamping pressure in said clamping cylinders and to convey said pressure to said blankholder means.

5. In combination in a press, reciprocable pressing means for shaping a work piece, blankholder means movable relative to said pressing means for holding said work piece while it is being shaped, and a plurality of clamping cylinder-piston-assemblies operatively connected with said pressing means and said blankholder means and operable in response to a relative movement of said pressing means and said blankholder means for creating and exerting clamping pressure on the latter, each of said clamping cylinder-piston-assemblies comprising one cylinder and two co-

operating plungers, one of which is stationary, while the other is movable in unison with said blankholder means.

6. In a press, a press frame, a press platen for exerting working pressure on a work piece, a blankholder means for holding said work piece, plunger means stationary with said frame, plunger means stationary with said blankholder means, and cylinder means stationary with said platen and reciprocable over said plunger means.

7. In a press, a press head, a press platen, a blankholder connected to and movable relative to said platen, first plunger means stationary relative to said press head, second plunger means stationary relative to said blankholder means, and cylinder means stationary relative to said platen and reciprocable over said first and second plunger means.

8. In a press, a press head, a press platen reciprocable relative to said head, blankholder means reciprocable relative to said head and said platen, plunger means stationary relative to said head, plunger means stationary relative to said blankholder, and cylinder means reciprocable over both of said plunger means and stationary relative to said platen.

9. In a double acting press, a press head, a reciprocable press platen, blankholder means supported by and movable relative to said platen, cylinder means stationary relative to said platen, first plunger means stationary relative to said head and extending into one end of said cylinder, second plunger means stationary relative to said blankholder and extending into the other end of said cylinder.

10. In a press, a press head, a press platen reciprocable relative to said head, blankholder means connected with and movable relative to said platen, cylinder means carried by said platen, plunger means stationary relative to said head and extending into said cylinder means, second plunger means stationary relative to said blankholder means and extending into said cylinder, said last mentioned plunger means being hollow and adapted to telescope with said first plunger means.

11. In a press, a press head, a press ram reciprocable relative to said head, blankholder means associated with said ram and movable relative thereto, cylinder means associated with said ram and reciprocable therewith, a first plunger means stationary relative to said head and extending into said cylinder means, second plunger means stationary relative to said blankholder and extending into said cylinder means and adapted in response to relative movement between said blankholder and said press ram to generate pressure within said cylinder.
